[57] CLAIM

The ornamental design for a beam balanced pumping unit, substantially as described as shown.

DESCRIPTION

FIG. 1 is a perspective view of a beam balanced pumping unit showing my new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and

FIG. 7 is a bottom plan view thereof.
